UNITED STATES PATENT OFFICE.

GEORGE F. SISBOWER, OF FLUSHING, AND LOUIS E. PITTONI, OF NEW YORK, N. Y.,
ASSIGNORS TO MANHATTAN-ROME COMPANY, BRANCH OF ROME METALLIC BED-
STEAD CO., OF LONG ISLAND CITY, NEW YORK, A CORPORATION OF NEW YORK.

COUCH BED.

Application filed April 27, 1921. Serial No. 464,906.

To all whom it may concern:

Be it known that we, GEORGE F. SISBOWER, a citizen of the United States, residing at Flushing, New York city, in the county of 5 Queens and State of New York, and LOUIS E. PITTONI, a subject of the King of Italy, residing at the city of New York, in the county of Queens and State of New York, have invented certain new and useful 10 improvements in Couch Beds, the following being a full, clear, and exact disclosure of the one form of our invention which we at present deem preferable.

For a detailed description of the present 15 form of our invention, reference may be had to the following specification and to the accompanying drawing forming a part thereof, wherein

Fig. 1 shows the form of telescoping couch bed heretofore in common use,

Fig. 2 shows our improved form thereof, and

Fig. 3 shows a detail.

Our invention relates to telescoping couch 25 beds and consists in certain improvements that are herein shown, described and claimed.

In the construction of couch beds it has heretofore been customary to make the 30 larger, outer section the stationary one and the smaller, inner section the movable one. In such an arrangement the "dressing" of the couch, consisting of a valance to cover the front of it, is secured at its top to the front edge of the stuffed mattress, but since the inside movable section necessarily projects a short distance in front of the stationary one the valance will not hang down smoothly and neatly. This will be understood 35 by reference to Fig. 1, wherein A¹ represents the larger stationary section and A² the smaller movable section. The necessity for longitudinally bracing section A¹ without resort to an angle brace, which is not admissible, calls for a brace-rod a⁴, and the said brace-rod a⁴ prevents the leg a³ and side bar a⁵ of the smaller inside section A² from moving flush with the front surface of the leg a⁶ and side rod a⁷ of the larger outer section 40 A¹. The two mattress layers are shown at C¹, C². They are hinged at the point c so that, when the section A² is drawn forward, layer C² can be folded over to lie on top of the said section. The valance D is se- 45 cured to the front edge of the layer C¹ and 55 when it hangs down, it is forced out by the protruding side-bar a⁵ and has not a neat and smooth appearance. Moreover, the valance must be lifted to give access to the inside section A² whenever that section is 60 drawn-out. That also causes the valance to lie on top of the drawn-out section A² when the mattress layer C² is folded over on that section. This causes the valance to become wrinkled by the compression of it be- 65 tween the mattress C² and the wire fabric of A². Finally both sections are provided with swiveled casters which tend to swivel as A² is drawn forward. That causes the inner section to bind in the outer one. So it 70 is necessary to work A² back and forth side- 75 wise in order to pull it out. It is our purpose to avoid these objections by means of the arrangement shown in Fig. 2. In this case the two sections are shown at B¹ and B². 75 The smaller inside section is made the sta- 80 tionary one, being for this purpose left with- out casters so that it will stand on the floor and resist movement. The larger outside section is made the movable one and is pro- 85 vided with non-swiveling rollers F as shown in Figs. 2 and 3. Moreover, the structure is reversed so that what was heretofore the back becomes the front. The brace b⁴, cor- 90 responding to a⁴ in Fig. 1, is now outside of 95 the leg b³ and can be drawn away from it as the couch is opened, which is now done by leaving B² stationary and pulling B¹ forward away from it. Moreover, the two mat- 100 tress layers are now hinged on the opposite 105 side at d. The valance G is secured to the lower mattress layer D¹ and can hang down straight and neatly without being bulged forward by the protruding side-bar of the inside section B², since that side-bar is pre- 110 vented from coming forward by the brace- 115 bar b⁴. Finally the unfolding of the mat- 120 tress is entirely independent of the valance 125 G. It is not necessary to lift the valance to 130 open out the bed and the valance is not 135 folded in under the mattress. When the two 140 sections are drawn apart the top layer D² 145 of the mattress is simply folded over on B² 150 which is left behind when B¹ is moved for- 155 ward, the valance in its normal down-hang- 160 ing position being moved with section B¹. 165 The fixed rollers F on section B¹ permit no 170 side play with respect to section B² with the

result that the drawing out of B¹ is direct and smooth and completely free from binding.

It will be perceived that without adding anything to the cost of the telescoping couch bed, we have made a pronounced improvement in its operation and appearance.

What we claim as new and desire to secure by Letters Patent is:

- 10 1. A folding mattress for telescoping couch beds comprising two sections hinged together along one longitudinal edge, a valance secured to the free edge of one section and having a portion extended upwardly over and normally covering the free edge of the other section when the mattress is folded, said valance having a portion draping downwardly from the first mentioned section in a position to extend over the front of the couch, whereby the movable section of the couch 35 may be drawn outwardly and the mattress unfolded without disturbing the valance.
- 15 2. A folding mattress for telescoping couch beds comprising two sections hinged together along one edge which normally coincides with the rear of the outside telescoping bed section, and a valance secured to the free edge of one section and having a portion extended upwardly over and nor-

mally covering the free edge of the other 30 section when the mattress is folded, said valance having a portion draping downwardly from the first mentioned section in a position to extend over the front of the couch, whereby the movable section of the couch 35 may be drawn outwardly and the mattress unfolded without disturbing the valance.

3. A folding mattress for telescoping couch beds comprising, two sections hinged together along the rear edges, a valance secured to the front edge of the normally lower section of the mattress when folded, said valance having a portion projecting upwardly a sufficient distance to cover the contiguous edge of the upper mattress section, 45 said valance also having a draped portion extending downwardly from the first mentioned section in a position to cover the front portion of the outside couch section, whereby the outside section of the couch may be 50 moved and the mattress unfolded without disturbing the valance.

Signed at Long Island City, county of Queens, State of New York, this 22nd day of April, 1921.

GEORGE F. SISBOWER.
LOUIS E. PITTONI.
